CLAIM

The ornamental design of a retaining wall block with side openings, as shown and described.

DESCRIPTION

FIG. 1 is a bottom perspective view of a retaining wall block with side openings showing my new design;

FIG. 2 is a top plan view thereof;

FIG. 3 is a bottom plan view thereof;

FIG. 4 is a front elevational view thereof; and,

FIG. 5 is a side elevational view thereof, the opposite side being a mirror image.

The broken lines in the drawings are for illustrative purposes only and form no part of the claimed design.
